UNITED STATES PATENT OFFICE

2,638,844

ROTARY PHOTOGRAVURE PRINTING APPARATUS

Angus Murray Halley, Moseley,
Birmingham, EnglandApplication June 29, 1950, Serial No. 171,154
In Great Britain May 8, 1950

5 Claims. (Cl. 101—169)

1

This invention has reference to improvements connected with rotary photogravure printing apparatus of the kind incorporating a doctor blade adapted to wipe excess ink from the periphery of an image cylinder and the present invention has particular reference to a means of fixing and adjusting such a doctor blade within a housing.

The object of the present invention is to provide a means of mounting the doctor blade within its housing which will admit of the ready removal thereof and also the adjustment of the blade within the housing in relation to the image cylinder with which it is associated so as to achieve line contact of the doctor blade with the periphery of the image cylinder throughout the whole of its length.

The invention consists of a means of mounting and adjusting a doctor blade within a housing characterised in that the doctor blade is held in a recess in a carrier by means of a plurality of expanding clamps the carrier being capable of a lateral sliding motion in a recess in the housing under the influence of eccentrics carried by rotatable spaced studs in the housing.

The invention will now be described with particular reference to the accompanying drawings in which:

Fig. 1 is a section through a housing incorporating the doctor blade and

Fig. 2 is a plan of a portion of the doctor blade housing seen in Fig. 1.

The housing 3 for the doctor blade is of quasi-cylindrical form and is provided with a longitudinal slot 4 so as to provide a recess within which is slidably accommodated a carrier 5, this carrier is provided with a longitudinal recess 6 within which the thin metal strip doctor blade 7 is mounted. The doctor blade is held against a wall of the recess 6 by placing a strip of heavier gauge metal 8 against its other face and then expanding between the strip 8 and the opposite wall of the recess 6 a plurality of expandable clamps 9 of the kind commonly known in the printing trade as quoins. These quoins are disposed at spaced intervals in the recess 6 throughout the length thereof and each comprises two sections 9^a having inclined interior faces with which to operate a wedge block 9^b engaged by a screw 9^c, it being appreciated that a tightening of the screw 9^c causes the wedge block 9^b to ride upon the inclined faces of the two parts 9^a so as to force them apart. Such an expandable clamp or quoin is well known in the printing trade and per se forms no part of the present invention.

The upper face of the carrier 5 is provided with a

2

plurality of longitudinal extending slots 5^a in which are rotatable the eccentric portions 10^a of the shanks of rotatable plugs 10 mounted in apertures 11 in the housing 3 at intervals corresponding to the spacing of the slots 5^a in the carrier 5. Also mounted in the carrier 5 are a plurality of pins 12 which pass through hollow bores in the plugs 10 and carry at their free ends lock nuts 13 whereby the plugs 10 can be restrained from rotation.

When it is desired to adjust the amount by which the doctor blade 7 protrudes from the housing 3 the lock nuts 13 are slackened and the plugs 10 are rotated so that the eccentric portions 10^a acting in the slots 5^a cause the carrier 5 and contained doctor blade 7 to slide laterally within the recess 4. This limited lateral movement of the carrier 5 relative to the housing 3 is permitted by a clearance obtaining between the pin 12 and the bore of the plug 10.

I claim:

1. In a rotary photogravure printing apparatus a means of mounting and adjusting a doctor blade within a housing comprising, in combination, a longitudinally recessed generally cylindrical housing, a carrier laterally slidably in the recess in the housing and having a rectangular recess along its exposed side, a doctor blade in the recess in the carrier, a plurality of expandable clamps in the recess in the carrier for retaining the doctor blade therein, said housing having a plurality of bores each of which intersects one side of the recess in the housing and is substantially perpendicular to such side and eccentric rotatable means in the bores of the housing and engaging the carrier for imparting a lateral movement to the carrier in the housing.
2. In a rotary photogravure printing apparatus a means of mounting and adjusting a doctor blade within a housing comprising, in combination, a longitudinally recessed generally cylindrical housing, a carrier laterally slidable in the recess in the housing, said carrier having a longitudinal rectangular recess in its exposed edge, a doctor blade in the recess in the carrier, a plurality of expandable clamps for retaining the doctor blade in the recess of the carrier, said housing having a plurality of bores intersecting a side of the recess in the housing, and a plurality of rotatable plugs in the bores in the housing having eccentric portions engaging slots in the carrier for imparting a lateral movement to the carrier in the housing.
3. In a rotary photogravure printing apparatus a means of mounting and adjusting a doctor

blade within a housing comprising, in combination, a longitudinally recessed housing, a longitudinally recessed carrier in the recess in said housing, a doctor blade in the recess in the carrier, a plurality of expandable clamps in the recess in the carrier between the doctor blade and a wall of the said recess, said housing having a plurality of bores intersecting a side of the recess in the housing and a plurality of rotatable plugs mounted in the bores in the housing and having eccentric portions engaging slots in the carrier.

4. In a rotary photogravure printing apparatus, a means of mounting and adjusting a doctor blade within a housing according to claim 3 incorporating pins fixed in the carrier and each accommodated in a bore in one of the plugs and lock nuts on the extremities of said pins for locking the plugs against rotation.

5. In a rotary photogravure printing apparatus, a means of mounting and adjusting a doctor blade within a housing comprising, in combination, a longitudinally recessed quasi-cylindrical housing, a longitudinally recessed carrier laterally slidable in the recess in the housing, a doctor

blade in the recess in the carrier against the one wall thereof, a metal strip in the recess in the carrier on the opposite side of the doctor blade, a plurality of spaced expandable clamps in the recess in the carrier between the strip and the opposite wall of the recess, a plurality of rotatable plugs mounted in bores in the housing that intersect a side of the recess therein, eccentrics on said plugs engaging slots in the carrier, pins in the carrier passing through hollow bores in the plugs and lock nuts on said pins.
